Rufus B. Fowler,

UNITED STATES PATENT OFFICE.

WILLIAM A. TURNER, OF WORCESTER, MASSACHUSETTS, ASSIGNOR TO
EDMUND CONVERSE, OF SAME PLACE.

SHEET-METAL KNOB.

SPECIFICATION forming part of Letters Patent No. 461,175, dated October 13, 1891.

Application filed June 1, 1891. Serial No. 394,665. (No model.)

To all whom it may concern:

Be it known that I, WILLIAM A. TURNER, a citizen of the United States, residing at Worcester, in the county of Worcester and State of Massachusetts, have invented a new and useful Improvement in Sheet-Metal Knobs, of which the following is a specification, reference being had to the accompanying drawings, in which—

10 Figure 1 represents the blank from which the base of the knob is made. Fig. 2 represents the crown-section of the knob. Fig. 3 is an elevation of the completed knob, and Fig. 4 is a vertical central sectional view of 15 the same.

Similar letters refer to similar parts in the different figures.

My invention relates to that class of sheet-metal knobs which are formed in two separate parts or sections known as the "crown" and "base," and it consists in certain features of construction, as hereinafter described, by which I secure certain advantages in the completed knob. These features of construction 25 relate, particularly, to the base of the knob and to the method of uniting the crown and base.

The blank from which the base of the knob is formed is represented in outline in Fig. 1 and has a solid central section A, including that portion of the blank bounded by the circular broken line A', and radial wings A², extending outwardly from said central solid section, each of said wings being provided 35 with projecting ears A³. It is best to make these ears semicircular in form for a reason hereinafter set forth. The edge of the blank between the ears A³ of each adjacent pair of wings A² is preferably bounded by a single 40 curved line A⁴. The blank is formed by the action of suitable punches and dies into the base-section of a knob of the desired form—such, for instance, as is represented at B, Fig. 3, and in central sectional view in Fig. 4. 45 The bottom or smaller end of the base B is drawn into its proper shape from the solid central section A of the blank. The wings A² are pressed into the circular flaring shape forming the upper and larger portion of the 50 base B, bringing the opposing edges B' of the

ears A³ into contact, leaving an opening B² below the ears A³ and the opening B² above the ears A³ and at the edge of the base B. The opening B² is preferably bounded at its sides by vertical and parallel lines A⁵. The 55 crown-section represented in Fig. 2 is provided with a flange C³, which is preferably cut apart at C' C', forming slits inclosing the section C², which is turned into the opening B² with the edges of the section C² abutting 60 against the edges A⁵ of the opening B², thereby preventing the rotation of the crown-section C upon the base-section B when the knob is turned for the purpose of screwing it upon an attaching screw or bolt. The ears A³ are 65 preferably semicircular in form, so that in case one of the radial wings should be drawn slightly more than an adjacent wing in the operation of forming the base, thereby bringing the projecting ear upon one wing in a higher 70 plane than the projecting ear upon its adjacent wing, the irregularity will not be so clearly disclosed by the abutting edges of the opposing ears.

Instead of turning the section C² into the 75 opening B² the flange C³ can be bent or indented at the opening B², so as to prevent the rotation of the crown upon the base. The object of the projecting ears A³ is to provide 80 abutting edges and prevent the approach of the wings toward each other and the base of the knob from being collapsed by a pressure applied upon the outside of the wings. The openings provided at the upper edge of the base also render the edge of the base slightly 85 elastic, allowing it to yield as pressure is applied in turning the edge C³ of the crown-section over the edge of the base-section, and as the pressure is removed from the flanged edge C³ after the completion of the knob the elasticity of the edge of the base-section will expand the ends of the wings firmly against the inner side of the flanged edge C³, securing a 90 tight fit between the edge C³ and the edge of the base-section inclosed therein, and this result is secured independently of the indentation of the flanged edge C³ into the openings formed in the edge of the base-section. 95

The openings B² are formed between the abutting edges of the projecting ears A³ and 100

the smaller end or bottom of the base, thereby providing means for ventilating the knob near the smaller or bottom end of the base by which it is attached to the stove or furnace door, 5 where the heat is greatest, and it also allows the surplus stock to expand in the process of shaping the lower or smaller section of the base from the central solid section of the blank.

10 What I claim as my invention, and desire to secure by Letters Patent, is—

1. In a sheet-metal knob, the combination of a base-section formed from a blank provided with radial wings, said wings having laterally-projecting and abutting ears, whereby said wings are prevented from being collapsed by outside pressure, said base-section being provided with openings at its edge, and a crown-section provided with a flanged edge 15 and having a portion of said flanged edge entering said openings, whereby the rotation of said crown-section on said base is prevented, and said base-section having holes below said projecting and abutting ears by which the 20 knob is ventilated, all substantially as described.
2. In a sheet-metal knob, the combination of a base-section formed from a blank provided with radially-projecting wings and having openings or holes formed in its sides between said wings and having abutting edges 25

between said holes or openings, and the edge of said base-section having openings between said wings at the edge of said base-section, whereby said wings are held from collapsing 35 under pressure and whereby the edge of said base-section is rendered slightly elastic, and a crown-section having a flanged edge turned over the edge of said base-section, forming the completed knob, substantially as described. 40

3. In a sheet-metal knob, the combination of a base-section provided with openings at its edge and a crown-section provided with the flanged edge and having a portion of said flanged edge entering said openings, whereby 45 the rotation of said crown-section on said base is prevented, substantially as described.

4. In a sheet-metal knob, the combination of a base-section B, provided with openings B² at its edge, said openings having parallel 50 sides A⁵, and a crown-section having a flanged edge which is turned into said openings to prevent the rotation of the crown upon the base, substantially as described.

Dated at Worcester, in the county of Worcester and State of Massachusetts, this 29th day of May, 1891.

WILLIAM A. TURNER.
